UNITED STATES PATENT OFFICE.

JOHN E. CASTER, OF CINCINNATI, OHIO, ASSIGNOR TO THE CINCINNATI GRINDERS, INCORPORATED, OF CINCINNATI, OHIO, A CORPORATION OF OHIO.

PROCESS FOR THE PRODUCTION OF SPHERICAL ARTICLES.

Application filed September 23, 1926. Serial No. 137,206.

This invention relates to a novel and improved process for the production of spherical articles such as balls for ball bearings and to the disclosed apparatus for carrying out of 5 said process.

One of the principal objects of the present invention is the provision of a novel process and apparatus for the production of such spherical articles which shall be capable of 10 appreciable stock removal as disclosed from the slow lapping processes hitherto commonly employed in performing work of this nature.

A further object of the invention is to provide for a continuous feeding through and 15 operation on the work pieces in a manner to insure gradual stock removal and permit of proper sizing of the pieces during the continuous progress thereof.

Another object of the invention is the 20 elimination of fixed work supporting members and the utilization in their place of the work pieces themselves to produce proper retardance of movement and resistance to the 25 cutting thrust of the grinding wheel.

Other objects and advantages of the present invention should be readily apparent by reference to the following specification considered in connection with the appended 30 drawings illustrating one apparatus for performance thereof, and it will be understood that any modifications in the specific structural details hereinafter disclosed may be made within the scope of the appended 35 claims without departing from or exceeding the spirit of the invention.

Figure 1 is an elevation of a grinder for carrying out the invention aforesaid.

Figure 2 is a fragmentary view of the 40 grinder as on the line 2—2 of Figure 1.

Figure 3 is a vertical sectional view illustrating the control of progress of the work pieces in the machine.

Figure 4 is a fragmentary view illustrating 45 a different position of the parts, and,

Figure 5 is a fragmentary view of the lower end of one of the guide tubes and control member associated therewith.

The present improved process comprises 50 primarily passing the articles to be operated on between the faces of a grinding member operating at high speed in the direction of general movement of the work, and a regulating member operating on the opposite side of 55 the work pieces at a slow or controlling rate

and in a direction to impart a rotating and twisting movement to the work pieces. The invention further contemplates the suitable retardance of movement of the work pieces in the direction urged by the grinding wheel, 60 so that proper time will be allowed for satisfactory grinding of the articles, not only at the points initially contacting with the grinding member, but also through the twisting action with all parts of the surface, so that a 65 true spherical form may be produced on the work.

The mechanism illustrating the carrying out of the invention is of the general centerless type, including a bed or base A, having 70 bearings for the grinding wheel B and the regulating wheel C, operating at the speeds and in the directions aforementioned. Means such as the screw D are employed to impart an in and out movement to the regulating 75 wheel as an entirety, while the wheel itself is capable of angular adjustment about a horizontal pivot being locked in such angularly adjusted position as by bolts E.

Disposed intermediate the bed A and slide 80 F for the regulating wheel is a second slide movable with or with respect to slide F, this latter slide G serving as a support for the work controlling mechanism. This work controlling mechanism includes a rotary shaft 85 10 provided with a plurality of notched disks or star wheels 11 above which rise work guiding tubes 12. These tubes have at their upper ends the joint mechanism member 13 which may be filled with work pieces 14 which 90 will then automatically feed down through the tubes and into the throat between the grinding and regulating wheels. To permit of engagement of the work pieces by the wheels, the tubes are slotted or cut away as at 95 15 and 16. The grinding wheel B is trued with a number of grooves 17 which is in transverse section for the contra-generic curve to be produced on the finished work pieces.

To control the rotation of the star wheel 100 11, shaft 10 has a sprocket 18 connected by chain 19, preferably through suitable reduction gearing driven from the regulating wheel shaft with the result that shaft 10 rotates at an appreciably slower rate than the 105 rate of rotation of the regulating wheel.

The progress of the work through the machine will be best understood by reference to Figures 3 and 4 from which it will be noted that in what may be termed the initial posi- 110

tion shown in Figure 3, a work piece is in the tube 12 and resting in one of the notches 21 of the star wheel, while a work piece, about four above that resting on the star wheel will be disposed within the grinding throat for final sizing as determined by the width of the throat and the arc of curve of the groove 17 of the grinding wheel. Continued rotation of the regulating wheel causes the star wheel 5 to turn in a counter-clockwise direction carrying a work piece 14 laterally through the discharge opening 22 of the tube 12 whence it passes out of the machine through chute 23. At the same time the ball immediately there- 10 above will slide down on the surface of the ball being ejected until it eventually comes to rest on one of the inclined portions 24 of the star wheel. Continued rotation of the wheel allows the column of work pieces to 15 gradually move downward.

It will be understood that as the work pieces gradually move downward they will pass from the upper portion of the tube where they are entirely out of engagement with the 20 grinding and regulating wheels to a portion of the tube where they enter into engagement with the grinding and regulating wheels at a point above the line joining the axis of the two wheels or in other words where the 25 throat is wider. The slow downward movement provided will then allow the work pieces to be ground off and shaped in this upper portion of the throat until eventually reduced to the prescribed size as they pass through 30 the narrowest portion of the throat. As they pass downward through the lower portion of the tube, they serve as a support for the work pieces thereabove which are being 35 acted upon by the grinding wheel. It will 40 also be noted that the downward movement of the work piece is controlled by the fact that while there is no positive and definite work rest the piece being operated upon is supported by the column of balls intermediate 45 the grinding position and the individual star wheel 11 for that particular tube then progresses downward in the grinding throat continuing as the work pieces move down from center point on the lowermost ball as 50 shown in Figure 3 to a contact with a high point of the star wheel and thence to the lowest part of the notch 21 in the star wheel. At this point the lowermost work piece is 55 ejected by rotation of the star wheel and for a time the star wheel itself forms a progressively receding limit for the downward movement of the column until it again starts to eject the ball when the ball forms this receding stop.

60 From the foregoing description the process of producing spherical articles by this method should be readily apparent and it will be seen that the balls are automatically fed between grinding and controlled members from a wider to a narrower part of

grinding throat by a controlled progress allowing their gradual grinding off or reduction in diameter as well as their rounding up; that subsequent to the compression of the grinding action they serve as a receding retardant for the progress of other work pieces being acted upon until they are finally consecutively ejected from their individual tubes. 70

I claim:—

1. The process of grinding spherical articles consisting in feeding blanks in a continuous stream between a formed grinding member and a work controlling member transversely of the common axial plane of 80 said members and from wider to narrower portions of the throat between said members, whereby a progressive gradual removal of stock is effected by removing the necessary excess material from the surface of the 85 blank.

2. The process of producing spherical articles consisting in feeding blanks in a continuous stream between a formed grinding member and a work controlling member and from wider to narrower portions of the throat between said members, whereby a gradual reduction in size is performed, and utilizing completed work pieces as a controlling retardant for the progress of the work piece to be operated upon. 90

3. The process of grinding spherical articles consisting in passing the same between a formed grinding wheel and a controlling member, forming a variable width work receiving throat and positively controlling the rate of progress of the work pieces through said throat. 100

4. A machine for producing spherical articles including a grinding wheel having a plurality of grooves formed therein, an opposed regulating wheel, guides extending intermediate the wheels in tangent relation to the operative face thereof, and means for controlling the passage of articles along the 105 guides. 110

5. A machine for producing spherical articles including a grinding wheel having a plurality of grooves formed therein, an opposed regulating wheel, guides extending intermediate the wheels in tangent relation to the operative face thereof and means for controlling the passage of articles along the guides, said means including an ejector device for successively checking the progress 115 of the work pieces and laterally displacing them with respect to the guides. 120

6. A machine of the centerless type for production of spherical articles including opposed grinding and regulating wheels, the 125 grinding wheel having work forming grooves in the operative face thereof, guides arranged tangent to said operative face of the grinding wheel and a shiftable stop for successively engaging work pieces passing be- 130

tween the guides subsequent to grinding thereof to control the rate and direction of movement of a series of pieces between the guides.

- 5 7. A machine of the character described including opposed grinding and regulating wheels and a work guide tangentially extended through the throat between said wheels, means progressively limiting the 10 movement of work pieces through the throat within the guides, and connections between said means and the regulating wheel for operating the work controlling means in timed relation to the rate of rotation of the 15 regulating wheel.

8. A machine of the character described

including opposed grinding and regulating wheels, the grinding wheel having a formed groove of contour to produce desired curvature on the work piece, a guide tube extending through the throat between the grinding and regulating wheels in alignment with the groove of the grinding wheel, the tube having cut-away portions whereby the wheels may engage a work piece within the tube and 20 a star wheel operative within the tube below the grinding throat for controlling the progress of work pieces through the tube, substantially as and for the purpose described. 25

In testimony whereof I affix my signature.

JOHN E. CASTER.
